UNITED STATES PATENT OFFICE

2,618,425

MACHINE FOR APPLYING AND SEALING
CLOSURES ON CONTAINERSHarry E. Stover, Lancaster, Ohio, assignor to
Anchor Hocking Glass Corporation, Lancaster,
Ohio, a corporation of Delaware

Application September 20, 1946, Serial No. 698,124

23 Claims. (Cl. 226—82)

1

The present invention relates to the sealing art and embodies additions to and improvements upon the machine of my prior application, Ser. No. 579,671 filed in the United States Patent Office on February 24, 1945, now Patent No. 2,529,199, and assigned to the assignee of the present application.

Certain of the improvements may be embodied in sealing machines generally but the preferred embodiment illustrating the invention utilizes vapor for forming a high vacuum in a container at the time the closure is sealed to it. The injection of the vapor at and shortly prior to the time of sealing reduces the amount of vapor required, reduces the amount of condensate both inside and outside the package and increases the vacuum within the package. As described in my prior application, steam superheated to a high temperature is utilized to sterilize the head space and the inside of the closure, to reduce the quantity required, to reduce the amount of resulting condensate, to form a higher vacuum, and to otherwise improve the sealing operations.

An object of the present invention is to provide an improved sealing machine.

Another object of the invention is to provide an improved means for obtaining a high vacuum in a sealed package by utilizing vapor.

Another object of the invention is to provide improved means for superheating the vapor injected into the containers at and prior to the time of sealing.

Another object of the invention is to provide improved means for eliminating or minimizing the jamming of jars at the entrance to the machine.

Another object of the invention is to provide improved means for retaining the parts in synchronism and for restoring synchronism when certain parts are stopped without stopping other parts.

Another object of the invention is to provide an improved driving means for the various parts of the machine.

Another object of the invention is to provide an improved driving means for the helicoid which guides and spaces the containers passing through the machine.

Another object of the invention is to provide an improved drive for the head spacer and the star wheel.

Another object of the invention is to provide improved means for applying the closures to the containers.

Another object of the invention is to provide resilient means co-operating with a cap placing

2

fork to provide a better setting of a closure on a container.

Another object of the invention is to provide magnetic means co-operating with the cap applying means to obtain an improved cap placing operation.

Another object of the invention is to provide an improved superheater for obtaining high temperature steam for injection into the containers.

Another object of the invention is to provide improved superheating means with a more accurate regulation of steam temperatures.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

Fig. 1 is a perspective view illustrating a preferred embodiment of the machine with the head spacer mechanism omitted;

Fig. 2 is a top plan view of the machine as shown in Fig. 1;

Fig. 3 is a side elevation view of the machine including the head spacing mechanism;

Fig. 31 is a sectional view through another form of injector mechanism and superheater therefor;

Fig. 32 is a vertical sectional view through the superheater illustrated in Fig. 31;

Fig. 33 is a diagrammatic view illustrating the wiring connections for the superheaters and the thermostat therefor; and

Fig. 34 is a side elevational view illustrating the machine directly connected to a filling machine to be used as a unit therewith.

The preferred embodiment of the sealing machine illustrated in the drawings will be described in detail herein under the headings (1) General Description, (2) Frame and Drive, (3) Conveyor and Helicoid, (4) Head Spacer, (5) Cap Feed, (6) Cap Placing Means, (7) Injector-Superheater, (8) Pressure Head, (9) Combination Filling and Sealing, and (10) Operation.

General description

As a convenience in understanding the invention, a short description will now be given of the major parts of the machine before giving detailed descriptions thereof. Referring more par-

ticularly to Figs. 1 to 3, the preferred embodiment of the machine is illustrated with a base 1 which serves to house the drive in the lower part of the machine and to support a table 2 with its associated mechanisms. A superstructure 4 vertically adjustable with respect to the table carries parts of the machine.

A conveyor 5 extends longitudinally over the table and over the sprockets 6 mounted on the extensions 7 which are secured to the ends of the base 1. An adjustable guide rail 8 extends along one side of the conveyor, and a helicoid 9 and adjustable rail 120 along the other side of the conveyor. A device or bumper 10, having resiliently mounted fingers 11 thereon, and a retarder 12 co-operate with the helicoid 9 in starting the containers through the machine. The conveyor carries the containers into a star wheel 14 which co-operates with the helicoid in holding the containers in upright position as they pass the cap feed 15 and its associated mechanism for placing a cap firmly on the rim of the container. As the container leaves the cap applying means it passes under a sealing head 16 which forces the closure completely down on the container so that the sealed package is ready for labeling and shipping.

The forward end of the superstructure 4 has a head spacer 17 mounted thereon with discs 30 which register with and extend into the mouths of the containers passing under the head spacer to displace any excess liquid in them so that each container will be filled substantially to the same level and so that all of the containers will have 35 at least a predetermined head space to facilitate a proper seal and a proper vacuum within the container. As the filled containers are carried away from the spacer on the conveyor they pass under the cap positioning means 15, also mounted 40 on the superstructure, where a cap is forcefully placed on the rim of the container. Just before the cap is forced down and while one side of the cap is spaced from the rim of the container, steam is injected under the side of the cap until it is applied to the container in order 45 to displace the air therein with vapor and to form a vacuum seal when the vapor condenses. The mechanism 15 preferably applies sufficient pressure to the closure to seat it firmly on the 50 rim of the container and to form a vacuum seal thereon when the vapor within the head spacer condenses, which is practically simultaneous with the placing of the cap firmly on the container. The pressure head 16 later forces the closure completely 55 down on the container. Preferably the vapor is highly superheated to sterilize the inside of the closure and the head space at the time of sealing and to minimize the amount of steam required and the resulting condensation.

Frame and drive

Referring particularly to Figs. 1 to 9, a description will now be given of the drive connections to the operative parts of the machine. Other features of the drive connections for the particular parts will be described in more detail in the description of such parts.

The interior of the machine and the drive connections are shown more particularly in Fig. 4, 70 which is a vertical section along the line 4—4 of Fig. 2, in Fig. 6 which is a horizontal section through the base along the line 6—6 of Fig. 3, and in Fig. 9, which is a horizontal section through the superstructure along the line 9—9 of Fig. 3.

Referring more particularly to Figs. 4 and 6,

the base 1 has mounted therein bearings 19 for supporting a pair of vertical shafts or columns 20 which extend through the table 2 with their upper ends secured to the superstructure 4 of the machine to adjustably support it and the parts thereon. Threaded members 21 are adapted to raise and lower the vertical columns 20 when bevel gears 22 at their lower ends are rotated by means of a handwheel 24 on shaft 25 having bevel gears 26 thereon meshing with bevel gears 22. In this manner the superstructure may be raised and lowered to accommodate different heights of containers.

The motor for the machine and the reducing gears are carried in the base of the machine and comprise a motor 27 (Figs. 4 and 6) having a pulley 28 carrying a belt 29 extending about a pulley 30 forming a part of the reduction gears 31. The motor is preferably slidably mounted as shown at 32 (Fig. 4) so that it may be moved toward and away from the reduction gears 31 by means of a handwheel 34 on shaft 35 which is threaded into the motor base. In this way a constant speed motor may be used and the speed of the machine varied by operating the handwheel 34 to change the position of the motor with respect to the reduction gears. A detailed description of the speed change mechanism is not necessary as it is a common form of drive sometimes known as a "Reeves" drive.

Referring more particularly to Fig. 5, means are shown for disconnecting the drive from the entire machine when excessive overloads are encountered to prevent breaking of parts of the machine. As illustrated in the preferred embodiment, the pulley 30 is connected to the reduction gears through the intermediation of a disc 36 secured thereto by a shear pin 37 mounted in bushings 38. When an excessive overload is encountered the pin 37 shears and stops the machine. This, of course, does not occur frequently and in such emergencies the shear pin may be replaced very quickly by removal of the disc 36 and inserting another pin.

The speed reducer 31 has a vertical shaft with a bevel gear 39 thereon meshing with a bevel gear 40 on shaft 41. Shaft 41 is mounted in bearings 42 and extends horizontally through the upper part of the base of the machine in suitable position to be connected to other parts of the machine.

A worm gear 44 on shaft 41 (Fig. 6) meshes with a gear 45 on shaft 46 carrying the star wheel 14. The star wheel preferably comprises two stars 14a and 14b mounted on the opposite sides of the member 14c and spaced a substantial distance from each other to retain the containers in upright position. A cover plate 14d holds the keyed member 14c in place.

A bevel gear 48 also on shaft 41 meshes with a bevel gear 49 on shaft 50 to drive the helicoid 9 through a chain of gears described hereinafter.

A gear 52 also on shaft 41 meshes with a gear 54 on shaft 55 to drive the conveyor 5 through the reduction gear 56 (Fig. 2).

A bevel gear 59 (Fig. 4) meshes with a bevel gear 60 on the vertical shaft 61 to drive the superstructure parts by means of a bevel gear 62 slidably keyed to shaft 61 and meshing with a bevel gear 64.

Referring more particularly to Fig. 9, illustrating a horizontal section through the superstructure, the bevel gear 62 on shaft 61 meshes with bevel gear 64 on shaft 65 for driving the pressure head 16. The bevel gear 64 on shaft 65

meshes with a bevel gear 66 on shaft 67 which in turn has a gear 68 (Fig. 4) on its end meshing with gear 69 on shaft 70. The shaft 70 has a 45 degree angle gear meshing with a similar gear 72 on shaft 74, which in turn has a 45 degree angle gear 75 meshing with a similar gear on the vertical shaft 76 to which the cap feed is connected at its upper end 77 (Figs. 4 and 10).

The shaft 70 (Fig. 9) also has a bevel gear 78 at its end meshing with a bevel gear 79 on a horizontal shaft 80 which drives the head spacer 17.

By means of the drive connections described generally above, the star wheel, the conveyor and the vertical shaft 61, leading to the superstructure, are driven from the horizontal shaft 41 in the upper part of the base of the machine. The sealing head, the head spacer and the cap feed are driven from shafts 67 and 70 in the superstructure of the machine operated by bevel gear 62 on the vertical shaft 61. The features of the drive for these several parts will be described in greater detail in the description of the respective parts.

Conveyor and helicoid

The conveyor 5 may be of any suitable type, preferably composed of a series of plates as described in my prior application Ser. No. 579,671. Suitable sprockets 6 (Fig. 3) mounted at the ends of extensions 7, secured to the base, carry the conveyor, one of the sprockets being driven through the reduction gear 56 operatively connected to shaft 55 which is connected to the machine drive. The table 2 supports the conveyor as it passes through the machine so that containers placed on it are carried through the machine where the several operations are performed in the sealing of them.

It is desirable that the containers be spaced a predetermined distance so that they may register with the discs of the head spacer 17 and with the recesses in the star wheel 14 as they pass through the machine. A helicoid 9 (Figs. 1, 2, 3 and 7) is adapted to co-operate with the guide rail 8, retarder 12 and bumper 10 to achieve this objective.

The helicoid is shown in Figs. 7 and 8 comprising a hollow member tapering slightly at its forward end as shown at 82 with a helical fin 84 extending thereabout. The helicoid is mounted upon a pair of swinging members 85 and 86. The swinging member 85 is mounted on a bolt 87 in bracket 88 and is held in proper position by a second bolt 89 mounted in a slot 106 (Fig. 1) in the bracket 88. The upper end of the swinging member 85 has a protruding bearing 90 extending into the tapered end of the helicoid. The opposite end of the helicoid extends over the end of a member 93 seated on the protruding end of the shaft member 92 keyed to a gear 94. The gear is held on the shaft by the bushings 95 bolted to the swinging member 86. The bushing 95 has a hollow center with a threaded member 96 closing one end and a pin 97 closing its other end, said pin having a cammed or inclined end 98 engaging the inner of two balls 99, the outer one projecting into a recess 100 in the member 93. The pin 97 is forced into its outer position by a spring 101 whose tension may be regulated by the threaded member 96. Should the containers jam in passing through the machine, the pin 97 will be forced back against the spring 101 and the upper ball forced out of the recess 100 so that the helicoid will stop. Each time the ball 99 en-

gages the recess, pressure will be applied to rotate the helicoid and if the resistance has been released the helicoid will start again properly synchronized with the head spacer. If desired, a disconnecting means similar to that described hereinafter with respect to the head spacer and the cap feed may be utilized instead of the one just described.

The swinging member 86 is mounted about a hollow projection 102 fitting in a bearing 104. A bolt 105 extends through a slot 106 (Fig. 1) permitting the member 86 to be swung in the bearing 104 about shaft 107. The bolt 105 also carries a gear 108 which meshes with gear 94 and 109. Thus the member 86 may be adjustably 15 swung in the bearing 104 without interfering with its drive.

The shaft 107 has a bevel gear 110 on its end meshing with a bevel gear 111 on shaft 112 (Fig. 6) which in turn has a gear 114 meshing with a gear 115 on shaft 50. The shaft 50 is connected to the motor drive by means of a bevel gear 49 thereon, and by bevel gear 48 on shaft 41, which is the horizontal shaft at the base of the machine and which is connected to the motor drive through bevel gears 39 and 40 and reduction gear 31.

The mechanism described can be easily connected to the machine drive by a shaft at the center of the machine and permits the helicoid to be swung toward and away from the conveyor to accommodate containers of different sizes. Usually the larger containers have greater height and as the helicoid moves away from the conveyor the height of it increases, which is helpful in having its contact nearer the middle of the jars. The helicoid may be removed and replaced by removal or loosening of the swinging arm 85 and may be adjusted in position by loosening the nuts 89 and 103.

A so-called bumper 10 (Fig. 2) facilitates entry of the jars into the machine. Preferably the bumper is substantially the same as that illustrated in my prior application Ser. No. 579,671, and comprises a series of resiliently mounted fingers 11 which afford substantial resilience and permit the containers to adjust themselves in moving into the helicoid. A guide rail 8 (Fig. 2) extends from the bumper through the machine and is mounted by means of bolts 116 in inclined slots 117 for adjustment to and from the conveyor to accommodate different sizes of containers. By reason of the inclined slots 117 the adjustments retain the rail parallel to the median line of the conveyor.

A retarder 12 is mounted on the forward end of the rail 8 and may comprise a resiliently mounted member 118 held in the position shown in Fig. 2 by means of a spring 119 effective upon the end thereof beyond its pivot. The purpose of the retarder 118 is to offer a resistance to the movement of each container so that the container is forced back into contact with the fin on the helicoid. In this way the container will register accurately with the discs of the head spacer.

The guide rail 8 preferably extends from the bumper 10 to the star wheel 14 and from the star wheel past the pressure head of the machine. A pair of spaced guide rails 120 (Fig. 1) are mounted similarly to the guide rail 8 and extend on the helicoid side of the conveyor from the helicoid past the pressure head.

The containers entering the machine engage the spring fingers 11 of the bumper 10 and the

forward end of the helicoid 9. Any jamming between the containers and the helicoid will be relieved by the spring fingers moving outwardly. By the time the container reaches the end of 5 the bumper 10 it is between adjoining fins of the helicoid. As it leaves the bumper 10 it engages the inclined forward surface 118 of the retarder 12 which forces the container back against the fin of the helicoid, if it is not already in that position. The container then will move with the conveyor under the head spacer and through the machine.

Head spacer

The features of the head spacer and its drive are shown more particularly in Figs. 9 to 13. The head spacer proper may be of the type shown in my prior application Ser. No. 579,671 and is not described in detail herein. The machine 10 may be used without the head spacer as illustrated in Fig. 1, in which case the connection therefor may be closed over by a plate 13.

The discs 121 (Fig. 3) may be of rubber, metal or any other suitable material. Rubber has the 25 advantage of minimizing the likelihood of damage to the containers in the event that a head does not register accurately with the mouth of the container. The head spacer is mounted in a cover or casting 122 having a projection 124 at 30 one end fitting into a bearing 125 in the superstructure of the machine. This permits the casting 122 and the head spacer to be tilted about its rear end for inspection and in case a disc engages the rim of a container. The level of the head-spacer is determined by a set screw 126 (Figs. 3 and 9) fitting in a bracket 127 and resting upon a projection 128. The drive shaft 80 for the headspacer extends through the bearing in the protruding member 124 of the casting 122. One 40 end of the shaft 80 carries a bevel gear 79 and the opposite end carries a sprocket 139 which is bolted to a disc or collar 131 (Fig. 11). The collar carries a pair of arms 132 (Fig. 12) pivoted at 134 with rounded projections 135 which may be in the form of rollers at their opposite ends. A second collar 137 forming a part of a bushing 138 has a pair of recesses 139 therein adapted to receive the rounded ends 135 of the members 132. Suitable springs 140 hold the rounded members 135 in the recesses 139 under normal conditions. A suitable synchronizer 142 similar to that described in my said prior application may be utilized for synchronizing the head spacer with the drive; that is, changing the relative position 50 of the shaft 80 with respect to the collar 137, or the same result may be achieved by loosening the nut 144 and adjusting the parts and then tightening the nut 144 to hold the parts in position.

By means of the drive connection shown in detail in Figs. 11 and 12 and described above, the arms 132 will raise whenever excessive resistance is encountered in driving the head spacer and thus disconnect the head spacer from the machine drive. The tension of the springs 140, the depth of the recesses 139 and the shape of the driving end thereof are such that the arms will raise on an excessive resistance to operation. The recesses are spaced so that when the drive engages again after the resistance is removed the head spacer will be in synchronism with the containers; in other words, the movement of the head spacer discs in half a revolution of the sprocket will be the distance between two head spacers or a multiple thereof. The bevel gear

79 on the end of the shaft 80 meshes with the bevel gear 78 on shaft 70 which is operatively connected to the drive of the machine as described hereinbefore.

Cap feed

As the filled containers leave the head spacer, the discs have entered the containers and displaced a predetermined amount of the contents where the container is too full so that a definite head space remains in the container. The containers then pass to the station where a cap is placed on and pressed partially down on the container. The closures may be of the general type shown in the Norman N. Holland Patent No. 1,909,406 owned by the assignee of this application. The closures pass down a chute, as shown more particularly in Figs. 15 and 21, where the lower edge of the closure engages the rim of the container and the movement of the container pulls the closure out of the chute.

Before describing the preferred embodiment of means for placing the closure on the container, the mechanism for automatically feeding the closures to the position shown in Fig. 15 will first be described. It will be understood, of course, that the closures may be fed by hand or by any suitable type of cap feed, but the preferred embodiment has novel features rendering it particularly applicable for the desired purposes. The cap feed for delivering closures to the inclined guideway 150, shown more particularly in Fig. 16, while described herein, is claimed in a subsequent application, Serial No. 118,802, filed September 30, 1949, owned by the assignee of the present application.

Referring more particularly to Figs. 15, 16, 21 and 22, there is shown a chute 150 which preferably has at least a hardened bottom surface or is made of a hardened metal to prevent the edges of the closures from chipping pieces of metal from it and to prevent undue wear upon it. As the closure is dropped in the upper end of the chute, it slides down to the position shown in Fig. 15. The details of the mechanism for feeding closures one at a time is shown more particularly in Fig. 16, which is a section of the upper portion broken away from Fig. 15. A stack of closures 151 is held in position by upright rods 152 with the bottom closures in the cylindrical recess 154 in Fig. 16. One edge of the bottom closure rests on the bottom of the chute 150 and the other edge of the closure rests on a latch member 155 having a sharp edge 156 at its end engaging under the edge of the closure as shown in Fig. 16.

When the latch member 155 is in the position shown in Fig. 16, closures cannot be fed by the device. When the latch member is moved toward the right, the edge of the bottom cap drops down to the rotary "cutter" 157 which has a tongue 158 adapted to slide between the bottom closure and the closure immediately above it so that the bottom closure upon further rotation of the cutter 157 will move down along the helicoid channel 160 until it drops into the chute. The bottom of the stack is held in position by the upper side of the tongue 158. Continued rotation of the cutter 157, until the latch member 155 stops the supply, will feed caps consecutively into the chute, one cap for each revolution of the cutter. The cutter is driven continuously by means of the 45 degree angle gear 161 on shaft 162 meshing with a similar gear 164 on shaft 165 which is connected to a continuation shaft 165a at 163 to facilitate removal and replacement of

the cap feed as a unit. The extension shaft 165a also has a 45 degree angle gear 166 (Fig. 14) meshing with a similar gear 167 on shaft 168 which is operatively connected to the cap feed drive 17 shown in Fig. 4 on shaft 76 connected to the horizontal drive shaft in the superstructure of the machine.

It is desirable to feed the closures one at a time as each container approaches the closure-applying position. This is achieved herein by movement of the latch member 155 as each container passes a particular position. Referring more particularly to Figs. 15, 21 and 22, a lever 170 is shown pivoted at 171 having an inclined surface 172 adapted to be engaged by a container as it moves along the helicoid on the conveyor. When the container presses the lever 170 outwardly the projection 173 on the lever engages an arm 174 on a vertical shaft 175 (Fig. 22) which in turn moves an arm 176 on shaft 175 to the right, pushing link 177 to the right and rocking a shaft 178 by means of an arm 179 thereon. The arm 180 on shaft 178 pulls the slidably latch member 155 to the right, releasing a cap at the bottom of the stack which is fed by the rotary cutter 157 to the cap chute, as described hereinbefore. The cap slides down the chute sufficiently fast to be in position when the container, which has tripped the cap feed, reaches the end of the chute.

For convenience in inspection, the cap feed is pivotally mounted on a shaft 182 (Fig. 16) so that it may be swung about this shaft for inspection of the interior of it after loosening the wing nut 184 and swinging it out of its recess to permit the cap feed to be raised.

The shaft 175 has a pair of flat members slotted as shown at 185 and bolted together at 186 so that the length of it may be adjusted when the height of the superstructure is adjusted to accommodate different sizes of containers.

It is desirable to have a convenient means for synchronizing the cap feed with respect to the containers passing on the conveyor so that the tongue 156 will be in proper position when the trip and latch member are operated. A suitable mechanism for this purpose is shown in Fig. 17. The gear 164 rotates shaft 165 and is fixed on the shaft by means of a collar 188 having one or more teeth or projections 189 which bite into a part 190 fixed to the gear 164. The threaded cover 191 may be removed and the nut 192 loosened so that the shaft 187 may turn freely within the gear. When the proper relation of the parts has been determined the nut 192 may be tightened, which fixes the parts in the desired position. This is a convenient means of synchronizing the cap feed with the container trip.

In case the caps should jam, it is desirable that the cap feed be disconnected without disturbing the synchronism previously fixed. This is achieved by means of a device 194 shown in Fig. 14 which may be identical except for size with the overload device shown in Figs. 9 to 11 for the head spacer. In view of the identity of the parts, a detailed illustration and description are not believed to be necessary.

Cap placing means

After the closure has been delivered to the end of the chute, as shown more particularly in Figs. 15 and 21, it is desirable to place the closure on the container so that it rests substantially flat on the rim thereof and forms a temporary seal on it. It is not necessary at this point that

the closure be forced completely on the container. It is sufficient for satisfactory operation merely to place the closure on the container so that the gasket engages the container about its periphery. However, it is desirable that the closure be laid on with some force so that a good contact between the closure gasket and container rim results and so that the formation of the vacuum by the condensation of the steam will be able to hold the closure on until it is forced down by the pressure head 16.

The preferred embodiment of the mechanism for achieving this objective is illustrated in Figs. 29 and 30, but the mechanism shown in Figs. 15 and 18 to 21 may be used and will be described first for convenience. A fork-carrying member 195 is pivotally mounted on a pin 196 in brackets 197 and is held in its lower position by means of a spring 198 secured to one end of the fork at 199 and to the upper part of a bracket 200. The bracket 200 has a cross part 201 which limits the upward movement of the spring-attached end and the downward movement of the opposite end of the fork-carrying member 195 for engaging and pressing the closure on the container.

A supplemental member 202 is mounted beneath the fork-carrying member 195 on a pin 204. Its lower position as it moves about the pin 204 as a pivot is determined by a member 205. As the closure 151a drops to the bottom of the chute, the front edge engages the adjustable stops 150a as shown in Fig. 15a. The cover of the cap is in engagement with the lower end of the pivoted member 202 which has a magnet 206 engaging the cap cover to co-operate with the stops 150a to hold it in position and to prevent it from tilting downwardly. In this way the closure is held accurately in position and as the rim of the container engages the lower edge of the closure and forces it out of the chute the downward projecting side of the closure is raised upwardly over the stops 150a which in turn raises the pivoted member 202 upwardly together with the bar 205 and magnet 206. These hold the cap in proper position until it is engaged by the fork 193. The magnet 206 holds the bottom end of the cap in its upper position so that it will not engage the glass finish too low and also applies a slight retarding force which tends to hold the edge of the cap in contact with the rim of the container at the forward part of the rim of the container. The fork 193, when it is engaged by the closure, continues this operation with greater force and applies sufficient pressure to the closure as it passes over it to force it against the rim of the container sufficiently so that when the vapor condenses the closure will be held in position. The vapor condenses instantaneously sufficiently to create a vacuum for holding the closure.

The details of the member 202 are shown more particularly in Fig. 20 and the parts illustrated in Fig. 15 are shown in greater detail in Fig. 19.

The preferred embodiment of the cap placing mechanism is illustrated in Figs. 29 and 30 and has a magnet-carrying member 202a pivotally mounted on a pin 204a having its lower end in the form of a T with a pair of magnets 206a thereon. These magnets engage the closure at spaced positions from its middle and are more effective than the single magnet described above. Stop members 207 may be provided at the sides of the chute for engaging the edge of the closure to co-operate with the magnets in holding it in proper position. As the container moves the 75

closure out of the chute the lower edge will be raised over the stops 207. Preferably the stops 207 are in the form of discs secured to the sides of the chute by members 208 adjustably mounted in slots 208a with the edges thereof tapered inwardly and upwardly thus to co-operate with the magnets in holding the closure in position.

The discs 207 may be rotatable but they need not be. Where the discs are stationary, they may be turned as they wear at one point to present another wear surface. If desired, discs 208 of different sizes may be substituted to accommodate different sizes of closures. Where it is desired to use a closure of a substantially different size, a chute of different size may be substituted with a suitable size closure feed. The magnets hold the closure against tilting and the discs 207 co-operate with them in obtaining this objective and also, in combination with the magnets, serve as stops to limit the downward movement of the closure when it slides down the chute.

Another embodiment of the closure placing mechanism is illustrated in Figs. 27 and 28 which has advantages but has been found less desirable than the preferred embodiment including one or more magnets. The fork-carrying member 195b has a fork 193b tiltably secured to it by means of a bolt 209 having a bushing fitting into a bearing in the fork 193b to tiltably hold it in position. The amount of tilting may be controlled by a U-shaped recess 210 in the fork 193b and a tongue 211 projecting from the fork-carrying member 195b. This limited tilting movement permits the fork to adjust itself slightly for irregularities in containers, for containers slightly off the median line of the conveyor and for closures engaging containers with one side slightly higher than the other.

A leaf spring 212 is secured to the lower side of the fork-carrying member 195b by screws 214. The leaf spring projects down near the fork 193b to co-operate with it and may have its lower position limited by member 215 pivotally mounted on a pin 216. The member 215, the spring 212 and the fork 193b co-operate to place the cap on the container, leaving it in as nearly a horizontal position as feasible.

Fig. 28, for convenience in drawing, has been shown in horizontal position. It will be understood that the parts are inclined as shown more particularly in Figs. 15 and 21. Improved results may be obtained by each of the above devices for applying the closures to the containers and particularly the preferred embodiment illustrated in Figs. 29 and 30.

It will be understood that the fork 193b and the fork-carrying member 195b illustrated in Figs. 27 and 28 and described above may be used in the other embodiments of cap placing mechanisms described herein. Likewise the rotary discs 207 may be used in the other embodiments as a substitute for the stops 150a.

Injector-superheater

As the closure is placed on the container, it is desirable to inject vapor between the side of the closure and the rim of the container in order to form a vacuum within the container when the vapor condenses. It is also desirable that the vapor be superheated to a high degree, preferably to a temperature of 300° to 700° Fahrenheit in order to sterilize the head space and the inside of the closure, to obtain a higher and more satisfactory vacuum and to minimize the amount of condensate in the container.

13

One mechanism for achieving this result is illustrated in Figs. 15, 23 and 24. A casting or other head 217 is provided having a conduit or bore 218 on one side and a similar conduit or bore 219 on the other. Vapor or steam is delivered to one end of one conduit through a duct 220 which preferably is quite small, about one-eighth of an inch in diameter for example, so that steam under three or four pounds pressure may be delivered to the superheater and be reduced in pressure in passing through the duct. This simplifies the delivery of steam and gives a higher vacuum and better operation. The steam passes along the conduit 218 and at the end of the conduit passes upwardly through a duct 221 into a thermostat chamber 222 and out of the thermostat chamber through a duct 224 into the conduit or passage 219.

The opposite end of the conduit 219 is provided with a plurality of outlets 225 which direct steam beneath the closure as it is applied to the container. If desired, a series of vertical ducts 226 may be provided in the lower side of the conduit 219 to direct steam into the head space of the container as it approaches the cap applying station. The ducts 218 and 219 have suitable heaters therein, which preferably are electric heaters, for superheating the steam to the desired temperature. These electric superheaters 227 are controlled by a thermostat 228 located in the chamber 222. Since all of the steam passes through the thermostat chamber and is effective upon the thermostat, it will register the proper temperature of the steam at this point. By having the thermostat removed from the point of outlet of the steam it operates at a much lower temperature than the steam being injected into the containers. By having a thermostat at this point, it is possible to get proper operation with a less expensive thermostat because as the temperature, at which the thermostat is required to operate, goes up its accuracy decreases and its cost increases.

The device illustrated is simple in construction and can be bolted to the cap feed by means of a bracket 229 and a bolt 230. Superheated steam is directed over the mouth of the container just as the closure is being applied and produces a high vacuum and a sterile head space.

Another form of superheater is shown in Figs. 31 and 32 with a casting 217a with conduit or superheater chambers 218a and 219a. These conduits have superheating units 231 and 232 which superheat the steam. A thermostat chamber 222a is provided at the lower portion of the casting with a thermostat 234 therein and a duct or conduit 235 leading from the superheater chamber to the upper end of the casting to facilitate electrical connections to the thermostat. The lower end of the injector has a plurality of outlet ducts 225a adapted to direct vapor under the side of the closure as it is being applied to the container. The casting may also have a plurality of vertical ducts 236 for directing vapor into the mouth of the containers as they pass under the superheater. Preferably the space between the rim of the containers passing under the superheater and the bottom of the superheater at its lowest point is about $\frac{3}{2}$ of an inch. A suitable thermometer 237 is fitted into a duct or conduit 238 leading to the superheater chamber. The thermometer enables the operator to determine the temperature of the steam substantially at the delivery point. In this way a uniform temperature may be provided to give maximum results in the sealing operation.

14

If desired, a pressure gauge may be substituted for the thermometer.

The upper end of the casting has a chamber 239 into which the electrical connecting ends of the heating elements protrude to facilitate electrical connections. Likewise the electrical connection for the thermostat may be run through this chamber by means of the duct 235. Suitable threaded plugs 240 close the ends of the superheater chambers, and a plug 241 the end of the thermostat chamber. These plugs may be part of the thermostats and the superheaters, or the latter may have portions extending through apertures in them. A suitable cover plate 242 permits access to the chamber 239.

Steam is delivered to the superheater by a suitable attachment applied at the threaded aperture 244. Preferably the attachment has a relatively small aperture about $\frac{1}{8}$ of an inch in diameter so that the steam may be delivered through the attachment to the superheater at a pressure of three or four pounds or even more, with the small aperture serving as a reducing valve, permitting the steam in the superheater chamber to be at a reduced pressure. The steam passes upward along the duct 218a through duct 221a to the upper end of the superheater conduit 219a and thence through conduit 238 to which the temperature gauge 237 is connected and which leads to the thermostat chamber 222a and from it through the ducts 225 and 236 under the side of the cap and into the mouth of the container to fill the head space with the highly superheated steam as the closure is applied.

Preferably the electrical superheaters and the thermostat are connected in series electrically as shown in Fig. 33, the superheaters being 231 and 232 and the thermostat 234, as illustrated diagrammatically. Whenever the thermostat breaks the current, both superheaters are cut out. The control could be applied to a single superheater but in the preferred embodiment both superheaters are under the control of the thermostat. By having the thermostat exposed to all of the steam as it passes to the conduit 225 the temperature of the steam at the outlet of the injector may be accurately controlled regardless of conditions leading up to this point.

Pressure head

After the closures are placed on the rims of the containers and forced on sufficiently to create a vacuum seal when the steam condenses, the containers with the closures on them preferably pass under a head which forces the closures completely down on the containers. Any suitable pressure head may be used for this purpose, for example a pressure head similar to that of my prior application Ser. No. 579,671.

The embodiment chosen herein is illustrated more particularly in Figs. 9 and 25 and may comprise a pair of pulleys 245, one of which is keyed to the shaft 65 having a bevel gear 64 thereon meshing with the bevel gear 62 on the vertical shaft 61 (Fig. 4) operatively connected to the drive in the base of the machine. A suitable belt 246 extends about the pulleys with a pressure foot 247 effective on the lower strand of the belt so that suitable pressure may be applied to the closures as the containers pass under the belt. The belt, of course, is driven at the linear speed of the conveyor carrying the containers.

In order to facilitate changing the belt from time to time and to apply sufficient tension to the belt, the pulleys are held apart by a coil

spring 248 effective upon a member 250 pressing against a U-shaped bracket 251 which has its legs pivotally mounted on the shaft 65 about the ends of the pulley 255. The lateral movement of the member 250 is limited by a bolt 256 having its head in the recess 257. To facilitate the operation of the swinging member 251 it may have a roller 258 thereon. By raising the bracket 251 the pulleys may be brought closer together so that the belt 243 may be quickly removed and replaced. Thereafter by swinging down the bracket 251 into the position shown in Fig. 25 the proper tension is applied to the belt and the pressure head is ready for operation. The pressure foot 247 may be held in position by depending members 252 on studs 254, the members and studs being held in their lower position by springs 255.

Combination filling and sealing

Containers are filled prior to sealing with the products to be preserved therein. It is desirable in many cases that the sealing machine be operatively connected to a machine for filling the containers so that the two may operate as a unit.

Referring to Fig. 34, the sealing machine herein is shown operatively connected to a filling machine 260 by means of a shaft 261 operatively connected to the drive of the sealing machine at 262. The side cover on the sealing machine is removed to show the interior drive connection. The filling machine 260 may be of the type now sold on the market and commonly known as the "Mojonnier" machine. It will be understood, of course, that any suitable type of filling machine may be operatively connected as shown. Preferably the shaft 261 has a flexible or universal connection as shown at 264 to give greater flexibility. By the unitary combination the containers are filled, automatically delivered to the sealing machine and sealed with vapor to sterilize and vacuumize in a continuous operation. The product delivered to the containers may be hot, thus sterilizing the interior of the container, or the container may be heated prior to filling so that a completely sterile container is provided. The container reaches the sealing machine in a few seconds after being filled and the superheated vapor sterilizes the inside of the closure and the head space of the container so that a sterile package results with high vacuum therein.

Operation

In the operation of the machine, assuming that the machine has been adjusted for the proper height and size container, filled containers are placed on the left end of the machine, illustrated in Figs. 1 to 3, without any particular arrangement or spacing of them. These containers are moved by the conveyor 5 into the entrance between the bumper 10 and the helicoid 9. Any jamming of the containers at this point is taken care of by the resiliently mounted fingers 11 of the bumper which co-operate in getting the containers into the helicoid. For example, if the forward portion of the fin on the helicoid engages a container and presses it against the bumper 10, the spring fingers will yield and prevent any damage to the container. In addition, they will tend to force the container in proper position with respect to the helicoid.

After the containers pass the bumper, they engage the retarding member 118, resiliently mounted by a spring 119, which tends to hold the respective containers against movement on the

conveyor until they are engaged by the fin on the helicoid, thus positioning the container against the fin, in which position the mouth should accurately register with the discs 121 of the head spacer 17 (Fig. 3). These discs displace any excess material out of the container leaving at least a minimum head space in each container into which vapor may be injected and condensed to form a vacuum seal. Where the head space is too small, less efficient results are obtained in forming a vacuum and in making a seal.

After the containers pass the head spacer they next engage the cap trip 170 shown more particularly in Figs. 15 and 21 which is pressed outwardly about its pivot 171 and oscillates the arm 174 (Figs. 21 and 22), shaft 175, and the upper arm 176 thereon connected to the link 177. The link 177 is connected to the arm 179 on shaft 178 having the arm 180 thereon which engages the latch member 155 (Fig. 15) and moves it toward the left to release a closure from the bottom of the stack which is fed downwardly by the rotating cutter 157, the edge of the cap following the helical channel 160 therein. The released closure slides down the chute 150 (Fig. 15) and is stopped at the end of the chute. It is held in position there by the magnet 206 co-operating with suitable projections engaging the edge of the closure.

The closure is in the position shown in Fig. 15 when the container, moving along the conveyor, engages it. As the rim of the container engages the forward edge of the closure, the closure is tilted upwardly about its other side, raising the magnet supporting the arm 202 about its pivot 204, and as it moves further the closure engages the fork 193 on the fork-carrying member 195 which is pivoted at its middle and held in its downward position by means of a spring 196 attached to its opposite end. Continued movement of the container causes the resiliently mounted fork to pass over the periphery of the closure and to wipe it down on the container. In addition, the magnet tends to hold the forward edge of the closure in contact with the rim of the container so that the closure is held back slightly at all times to prevent it moving forward too far. Any excessive forward movement of the closure prevents the rear of the closure from registering with the side of the container when it is pressed down on the container. On the other hand, too much backward pull on the closure tends to tilt or overturn the container. The magnet 206 permits sliding movement with a slight force and at the same time is sufficiently effective to prevent the closure from dropping down too far and from moving forward ahead of the container. The magnet has been found quite effective and much more effective than springs and other devices. The closure-applying device, of course, has advantages for general use but it is particularly applicable for use in combination with the steam injector attached to it.

The means for injecting steam under the side of the closure as it is applied is shown more particularly in Figs. 15, 23 and 24. Steam is delivered to the superheater at the entrance 220 and passes along the conduit 218 to the opposite end thereof and thence through the conduit 221 into the thermostat chamber 222 and thence through conduit 224 into the superheater conduit 219. The opposite end of the conduit 219 has vertical ducts 226 which direct vapor into the container as it passes to the cap applying station

and also has a plurality of ducts 225 (Fig. 23) which direct vapor between the tilted closure and the rim of the container at the time the closure is wiped down on the container. This minimizes the amount of steam required as the containers pass at a very rapid rate—usually over 100 a minute—which means that only a part of a second lapses in the sealing operation and between sealing operations. The amount of vapor used may be reduced to a minimum which reduces the condensation within the head space. Excessive condensation is objectionable with many products. The superheaters 227 in the conduits 218 and 219 superheat the steam to a sterilizing temperature, usually considerably in excess of 240° F. which is sufficient to kill mold spores which later develop into mold. Temperatures of above 300° F. are very much desired and temperatures of 400° and 500° F. are preferred. Temperatures of 600° and 700° F. have been used and found very satisfactory, but it is not necessary to use such high temperatures to get excellent results.

A suitable light 33 is mounted back of the containers as they pass the cap feed so that the light will emphasize the passage of bubbles up through the contents of the container. As a result of the condensation of the steam in the head space and the resulting formation of a partial vacuum, any small air bubbles in the contents are expanded and drawn to the top. The light shining through the container gives a vivid indication of whether or not a vacuum has formed in the package. This enables the inspector or operator to spot and remove any containers which do not have a vacuum formed in them for any reason, and such containers may be removed and passed through the machine a second time. It likewise enables the operator to stop the machine for adjustment the instant that the machine fails to form vacuum seals. Preferably the light 33 is connected in parallel with the heaters so that when the heaters are cut off the light will be cut off. This minimizes the chance of the heaters being left on overnight.

The containers with the closures on them pass under the sealing head 16 where a belt moving at the same speed as the conveyor 5 forces the closures completely down on the containers. The time interval between the application of the closure and the operation of the sealing belt is not of particular importance as the closure forms a temporary seal when the vapor condenses which occurs almost instantaneously upon placing the closure on the rim of the container.

When the machine is started with a particular size of container not used previously on the machine, or when it is desired to change the size of container, suitable adjustments are required in the machine. It is first necessary to raise or lower the superstructure 4 so that the rim of the container, when placed under the superstructure, is about $\frac{3}{4}$ of an inch from the lowermost portion thereof. This distance has been found to give the best results although a greater or less distance may of course be utilized. This adjustment may be made by means of the handwheel 24 (Fig. 4). In making this height adjustment the connection between the jar trip 170 (Figs. 22 and 26) and the cap feed is adapted to accommodate itself to this movement either by having the connection of the link 185 sufficiently loose to do so or by loosening the nuts 186 to permit the sliding movement necessary. If a different size of cap is required the chute 150 will take a fair range of variations, but if this range is ex-

ceeded a separate cap feed may be quickly applied by removing one and replacing it with another. The drive connection may be lifted off and the cap connection readily removed.

5 The vertical shaft 61 (Fig. 4) and the slidably keyed gear 62 thereon permit vertical adjustment of the superstructure without disturbing the driving connection.

In connection with the cap feed, it is desirable 10 to synchronize the jar trip with the cap feed so that a cap will be released at the proper time. This may be done by the mechanism shown in Fig. 17 wherein the nut 192 is loosened and the cap feed moved until it is in the proper position with 15 respect to the other parts whereupon the nut 192 is tightened, causing the projection 190 on the collar 188 to bite into the part 190 and hold it in accurate position. If any unusual resistance is occasioned in feeding the closures, the slip clutch 194 (Fig. 14) will operate to stop the closure feed 20 until the resistance is removed and to start it again in proper synchronism.

Likewise in connection with the head spacer, 25 it is necessary for the discs 121 to register with the mouths of the containers. The synchronizing means for the head spacer is illustrated more particularly in Figs. 9, 11 and 12. The nut 144 may be loosened and the head spacer properly registered with the mouths of the containers when 30 in the helicoid and against the fin thereon. Thereafter the nut 144 may be tightened to hold the parts in position. The tightening of the nut fixes the disc 131 in position with respect to the shaft 80.

35 The pressure head is automatically adjusted in height with the height adjustment of the superstructure.

The sealing machine may be directly connected 40 with a filling unit as illustrated more particularly in Fig. 34, in which case the containers will pass from the filling machine directly into the sealing machine. The filling machine being driven from the sealing machine, the two will operate in synchronism and there will be no accumulation of 45 filled containers waiting to be sealed.

A convenient push button arrangement 3 is provided on top of the superstructure for starting and stopping the machine.

A suitable breather is adapted to equalize the 50 pressure within and without the superstructure, and a similar breather may be utilized in the base structure for the same purpose. These prevent the building of pressures due to temperatures which would tend to cause lubricating oils to leak 55 out. A preferred form of breather is shown in Fig. 4a and may comprise an apertured threaded insert member 265 which communicates with the atmosphere through a conduit 266, dome 267 and apertures 268. This type of breather 15 may be utilized at other desirable locations of the machine as well as at the location shown in Figs. 1 to 3.

It will be seen that the present invention provides 60 a simple, inexpensive machine for vacuum sealing of containers utilizing highly superheated vapor. The machine embodies improvements on and additions to my prior application Ser. No. 579,671. The closure placing means is more effective in setting the closures on the containers and improved operation results. The helicoid is simplified in structure. The drive for the helicoid is improved in position and construction so that the helicoid may be adjusted without affecting the drive connections. The entrance of the containers into the machine and accurate positioning

with respect to the helicoid has been improved by the combination of elements, including the retarding mechanism, and various changes and improvements have been embodied in the present machine.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. In a machine of the class described, the combination of an inclined guideway for receiving and delivering closure caps, a member at the lower end of the guideway having a plurality of spaced magnets thereon adapted to pass over the cover of a closure cap, as a container passes under the member and pulls a closure under it, to force the closure cap on the container, and means for yieldably mounting said member.

2. In a machine of the class described, the combination of an inclined guideway for receiving and delivering closure caps, means at the lower end of the guideway including a yieldably mounted member having a plurality of spaced magnets thereon adapted to pass over the cover of a closure cap, as a container passes under the member and pulls a closure under it, to force a closure on the container, and means at the lower end of the guideway for directing vapor under an edge of the closure cap as it is being forced on the container to form a vacuum seal when the vapor condenses therein.

3. In a machine of the class described, the combination of means for placing a closure cap on a container, an injector mechanism adjacent said means for injecting steam between the closure cap and the container as the closure cap is being placed on the container, said mechanism having a conduit therein, a superheater in said conduit, a chamber, a thermostat in said chamber, and means for directing substantially all of the steam passing through said conduit against the thermostat in said chamber to subject the thermostat to substantially all of the steam passing through the conduit.

4. In a machine of the class described, the combination of means for placing a closure cap on a container, an injector mechanism adjacent said means for directing steam between the closure cap and the container as the closure cap is being forced on the container, said injector mechanism having a plurality of adjacent conduits for conducting the vapor, heating means effective upon the vapor in said conduits, said injector mechanism having also a small chamber for housing a thermostat and ducts for passing all of the vapor leaving one conduit through said chamber.

5. In a machine of the class described, the combination of means for placing a closure cap on a container, an injector head adjacent said means for directing steam between the closure cap and the container as the closure is being placed on the container, and means for superheating the steam passing through it, the inlet to said injector head for the steam being a small aperture about $\frac{1}{8}$ of an inch in diameter so that steam may be delivered to the injector head under pressure and be expanded to a substantially lower pressure in the injector head.

6. In a machine of the class described, the combination of means for placing a closure cap on a container, an injector head adjacent said

means for directing steam between the closure cap and the container as the closure is being placed on the container, an inlet having an area of about $\frac{1}{50}$ of a square inch whereby steam at a pressure of three or four pounds may be delivered to the injector and reduced to a substantially lower pressure in passing through said inlet, and means for heating said atmospheric steam as it passes through the injector head to the injector end thereof.

7. In a sealing machine, the combination of means for placing a closure on a container, and a vapor superheater including a plurality of elongated chambers adapted to receive heating means, a chamber at the lower ends of said chambers adapted to receive a thermostat, an outlet from said thermostat chamber adjacent said means and adapted to direct vapor between the closure and container at the time the closure is placed on the container, and a conduit from the end of one of said superheater chambers leading to said thermostat chamber.

8. In a device for feeding closure caps, the combination of means for separating successive closures from a group of closures, devices for driving said separating means in a predetermined timed relation to other associated parts, means for disconnecting said driving means when excessive resistance is encountered, and means for establishing said predetermined timed relation between said driving means and said separating means when they are again connected.

9. In a device for feeding closure caps, the combination of means for separating successive closures from a group of closures, devices for driving said means including a member having a recess therein and a second member rotatable with respect to said first member, and means on said second member resiliently mounted for engaging said first member to rotate the two members together, said recess permitting the resiliently mounted members to become ineffective on excessive resistance to rotation and permitting said driving means to become effective in the same timed relation when said resistance is removed.

10. In a machine of the class described, the combination of an inclined guideway for receiving and delivering closure caps, means at the lower end of the guideway for accurately placing a closure on a moving container including a magnet movable over the closure during forward movement of the closure engaged by a moving container to retard the forward movement of the closure and to hold the inner front side of the closure in contact with the rim of the container at the forward part thereof and to position the rear of the closure in accurate clearing alignment with the rear part of the container rim as it is forced thereon, and means at the lower end of the guideway for directing vapor under the closure as it is being placed on the container to form a vacuum seal by rapid condensation of the vapor to hold the closure in the said accurately placed position.

11. In a sealing machine of the class described, the combination of an inclined guideway for receiving and delivering closure caps, means at the lower end of the guideway for accurately aligning and placing a closure on a container, including a pair of spaced magnets engaging with and slideable over the top of the closure during forward movement of the closure to retard the closure against movement by a vapor

jet directed toward the closure to thereby accurately align the closure and cause the rear thereof to clear the rear part of the container rim as it is forced thereon, and means below the magnets and at the lower end of the guideway for directing a continuous stream of vapor toward the closure cap and under the side thereof as it is being forced on the container to form a vacuum seal by rapid condensation of the vapor and to hold the closure on the container in the said accurately placed position.

12. In a machine of the class described, the combination of an inclined guideway for receiving closure caps, means at the lower end of the guideway for applying a closure cap on a container including a pivotally mounted member having a magnet adapted to engage and support the forward side of the closure as the closure is engaged by the container during its application to the container, and means at the lower end of the guideway for directing vapor under the side of the closure cap as it is being forced on the container to form a vacuum seal when the vapor condenses therein.

13. In a machine of the class described, the combination of means for placing a closure cap on a container, mechanism for directing steam between the closure cap and the container as the closure is being placed on the container, and means for superheating the steam passing through the mechanism, the inlet to said mechanism being relatively small so that steam may be delivered to the mechanism under pressure and be expanded to a substantially lower pressure in the mechanism.

14. In a machine of the class described, the combination of means including a pivoted V-shaped member for engaging the periphery of the closure cap to force the closure on a container and separately pivoted magnetic means adjacent said V-shaped member for magnetically engaging the top of the closure cap to support the forward side thereof and to cooperate with said first means as it is forcing the closure on the container.

15. In a machine of the class described, the combination of an inclined guideway for receiving closure caps, means including a pivoted substantially V-shaped member at the lower end of the guideway for engaging the closure cap to force the closure on a container, a magnet yieldably mounted at the lower end of the guideway for engaging the closure cap to co-operate with said V-shaped member and to support the front side of the closure, and means for directing vapor under the side of the closure cap as it is being forced by said V-shaped member on the container to form a vacuum seal when the vapor condenses therein.

16. In a machine for vacuum sealing closure caps to containers, the combination of means for placing a closure on a container and a vapor superheater including a heater chamber, an outlet adjacent said means for delivering vapor between the closure and container at the time the closure is placed on the container, and a thermostat chamber adapted to receive the steam passing from said heater chamber to said outlet, whereby substantially all the steam leaving said heater chamber will be effective on a thermostat mounted in said chamber.

17. In a machine for vacuum sealing closure caps to containers, the combination of means for sealing a closure to a container and a steam superheater including a plurality of adjacent

interconnected elongated chambers adapted to receive superheaters, an outlet adjacent said means for delivering steam between the closure and container at the time the closure is placed on the container, and a chamber adapted to receive a thermostat interposed between the end of one of said chambers and said outlet to receive the steam passing from one of said elongated chambers to said outlet.

18. In a machine for sealing closure caps to containers, in combination, means for sealing a closure cap to a container, a plurality of inclined elongated superheating chambers adapted to receive heating means, a chamber at the lower ends of said inclined chambers adapted to receive a thermostat, an outlet from said thermostat chamber adjacent said sealing means for delivering steam between a closure and a container at the time of sealing, and a conduit from the end of one of said superheater chambers leading to said thermostat chamber.

19. In a machine for sealing closure caps to containers, in combination, means for placing a closure on a container, a chamber adapted to receive heating means, heating means in said chamber, a second chamber at the end of said first chamber adapted to receive a thermostat, a thermostat in said last mentioned chamber, an outlet leading from said thermostat chamber adjacent said closure placing means adapted to direct steam between the closure and container at the time the closure is placed on the container, and a conduit from said heater chamber leading to said thermostat chamber.

20. In a machine for sealing closure caps to containers, in combination, means for applying a closure cap to a container, a plurality of heater chambers adapted to receive heating means, heating means in each of said chambers, a chamber at one end of said plurality of chambers adapted to receive a thermostat, a thermostat in said last mentioned chamber, an outlet leading from said thermostat chamber adjacent said closure cap applying means adapted to direct steam under the side of a closure as it is being applied to a container, a conduit from the end of one of said heater chambers leading to said thermostat chamber, and a thermometer operatively connected to said thermostat chamber and responsive to the steam substantially at said thermostat chamber.

21. In a machine of the class described, the combination of means for moving a container along a path, means adjacent to said path for supplying a closure cap to be applied to a container, and a forked member pivotally supported for swinging movement in a plane transverse to said path and having depending arms for engaging the opposite edge portions of the cap and pressing the same onto the container as it moves along the path.

22. In a machine of the class described, the combination of means for moving a container along a path, means adjacent to said path for supplying a closure cap to be applied to a container, a member having a pair of depending arms for pressing a closure cap downwardly onto a container moving along said path by passing over opposite edge portions of the closure cap, and a pin pivotally supporting said member to permit oscillation about said pin when engaged by a closure passing between said depending arms thereby to equalize the pressure applied to the opposite edges of the closure by said arms.

23

23. A mechanism in accordance with claim 22, which includes means for limiting the amount of said oscillation.

HARRY E. STOVER.
